UNITED STATES PATENT OFFICE.

JAMES FLETCHER, OF NEWNES, NEW SOUTH WALES, AUSTRALIA.

PERCUSSION ROCK-DRILL.

1,305,349.

Specification of Letters Patent. Patented June 3, 1919.

Application filed March 30, 1916. Serial No. 87,694.

To all whom it may concern:

Be it known that I, JAMES FLETCHER, subject of the King of Great Britain and Ireland, residing at Newnes, New South Wales, Australia, have invented certain new and useful Improvements in Percussion Rock-Drills and Coal-Cutters Operated by Fluid-Pressure, of which the following is a specification.

10 This invention has been devised to improve drills of the type used for rock and coal holing, nicking, drilling, or wedging in respect of the control of the plunger action in drills operated by compressed air or steam for the purpose of effecting a change in the length of stroke of the plunger at the will of the operator and to provide for optional cushioning and also to enable the plunger to be jiggled on a

15 short stroke for the purpose of relieving the cutting bit when it is working or jammed in a tight hole or channel, and adapting the machine to be worked most effectively on high, medium, or low pressure air or steam.

20 In the accompanying drawings, Figure 1 is a longitudinal section through the drill cylinder and valve chest;

Fig. 2 is a half sectional plan corresponding with Fig. 1;

25 Fig. 3 is a transverse section on line *a*—*b* Fig. 1;

Fig. 4 is a half transverse section on line *c*—*d* Fig. 1;

30 Fig. 5 is a transverse section on line *e*—*f* (Fig. 1);

Fig. 6 is a broken sectional elevation of manual control tube valve; and Fig. 6^a a transverse section through same;

Fig. 7 is a fragment sectional elevation 40 of portion of the main valve and of one head of the valve chamber;

Fig. 8 is an enlarged longitudinal section through the main valve chamber and main valve;

45 Fig. 9 is a half top plan and horizontal section through the main valve chamber and the main valve therein;

Fig. 10 is a transverse section taken at three different positions on Figs. 8 and 9.

50 The plunger head is shown in dotted position near the extreme outward end of its stroke in Fig. 1.

The cylinder chamber communicates with the main valve through two ports 22 and

55 23 located near its rear and forward ends respectively, the front port 23 being set a little backward from the extreme front end of the cylinder so as to insure the imprisonment of sufficient air in front of the plunger head to partially cushion the same and prevent actual mechanical contact between the plunger head and the cylinder end, a rubber ring buffer 82 being also fitted for this purpose.

60 The back port 22 merges directly into the aperture 25 on a plane face 27 on the side of the cylinder, on which plane face the valve casing 26 is bolted down. The front end port 23 communicates with the aperture 28 on the face 27, through a cored passage 65 24. A by-pass 29 connects the cored passage 24 to the cylinder chamber at 30 through a plug cock or valve 31, the stem of which is fitted with a hand lever or other device for turning the valve manually to 70 open or close it as required. The aperture 30 enters the cylinder at a point rearward of the front end port 23 a distance slightly exceeding the length of the plunger head.

75 A hole 32 is drilled through the solid 80 metal in the cylinder body parallel with the cylinder axis, and this hole is placed in communication with the cylinder through five by-pass holes, 33, 34, 35, 36 and 37 located preferably as shown in Fig. 1. 85

There may be a greater or less number of these by-pass holes, and they may be located differently from those shown in the drawing, but so as to operate similarly to those shown. The drilled hole 32 forms a 90

seating for the manual control tube valve 90 which is a neat fit in it and is rotatable by means of a spanner or hand lever engaged with its square stem end 38. This tube valve 90 has seven holes 39, 40, 41, 42, 95 43, 44 and 45 drilled through its wall. The disposition of these seven holes at four angular positions is shown in the detail section Fig. 6^a. The necessary number and

100 respective positions of the holes in the tube valve 90 depend upon the number and disposition of the by-pass holes 33—37 through the cylinder wall. The inner end of the tube valve 90 is reduced in section externally as shown at 46, and holes 47 105 are made through the reduced part of it to act as passage-ways from its bore 48 into a passageway 49 which leads up to the face 27.

110 A channel 50 is cut in the face 27. At

either end this channel aligns with holes 52 and 53 which are drilled radially through the wall of the valve chamber 26.

- If the tube valve 90 is turned to any position in which one or more of the holes 39 to 45 is not in alignment with one or more of the holes 33 to 37 in the cylinder wall, communication will not be established through any of the last mentioned series of holes to 10 the passageways 52 and 53 leading through the wall of the valve chamber, but in any of the four angular positions shown in Fig. 6^a one or more of the holes 39 to 45 will come into alignment with one or more of the holes 15 33 to 37 and establish communication through the hole or holes so brought into alignment between the interior of the cylinder and the said passageways 52, 53, leading into the valve chamber.
- 20 The action of the plunger will be governed by the adjustment of the valve 90, Fig. 6, in the way hereinafter described.

The valve chamber is cylindrical and the valve is of the usual multi-head piston type, 25 60 being the pressure inlet and 61 the exhaust outlet.

The inlet 60 (see Fig. 9) enters two annular spaces 62 and 63, and the exhaust 61 opens directly out of the central annular 30 chamber 64. The main face ports 25 and 28 communicate with the cylinder ports 22 and 23 respectively and are respectively led into the annular cavities 65 and 66. The valve chamber is closed by solid covers 67 35 and 67^x which are screwed home into its ends. In each of the covers is a small axial cylinder 68 68^x in which the close fitting plungers 69 69^x on the ends of the valve stem 70 slide. Annular grooves 71 and 71^x are 40 turned in each of the heads 67 and 67^x and these grooves communicate through radial passages 72 and 72^x with the cylinders 68 and 68^x at the respective ends of the valve chamber.

45 It will be noted on reference to Fig. 8 that the valve plunger 69 is home in its cylinder 68, and the passageways 72 open up communication between the grooves 71 and the end chamber 73. Therefore when the 50 valve is at this end of its stroke (see right hand end of Fig. 8) the plunger 69^x closes the holes 72^x, and there is no longer communication from the end chamber 74 through the holes 72^x, groove 71^x, passageways 53, 55 50, 49, and tube valve 90 to the cylinder 20. The main valve consists of a central stem 70 carrying upon it a central head 75 and two grooved heads 76 and 77 between said central head 75, and at either end, plungers 69 50 and 69^x. From the grooves in the heads 76 and 77, holes are drilled into the center of the stem and these holes communicate by the axial holes 79 and 80 with the cylinders 68 68^x in the valve chamber heads.

65 It will be noted that the plungers 69 69^x

are connected to the valve by stem portions 81 which are smaller in diameter than the plungers.

The operation of the drill plunger and valve is as follows:—

Assuming that the valve is in the position shown in Figs. 1, 7 and 8, and that the manual control valve, Fig. 6, is turned so that the ports 39 and 42 therein align with the ports 33 and 35, in the cylinder wall; 75 then the pressure service is opened so that the valve chamber 62 and 63 contain air or steam under pressure. Said air or steam will pass from the chamber 62 to the chamber 65 and thence through the face port 25 and the cylinder port 22 as shown by the arrows Figs. 1 and 8. Owing to the position of the valve, which as shown in the figures is in the extreme left position, pressure cannot pass from the chamber 63 to the cylinder 80 port 23, but the forward end of the cylinder is open through said port 23, the passageway 24 and the face port 28 and chamber 64 to the exhaust 61. Pressure acting on the back of the plunger will force it forward until its 85 rear end passes the port 33. Thereupon pressure will pass through the said port 33 into the axial hole 39 in the manual tube valve 90, and thence by the cored passage 49, face groove 50 and the port 52 the groove 95 71 and the holes 72 into the valve chamber 73. In the present position of the valve, air cannot pass through the hole 53 to the right hand end of the valve owing to the radial holes 72^x being closed by the plunger 69^x. 100 Pressure air or steam is however passed from the chamber 63 through the axial hole 80 in the valve stem and internal pressure is thus set up in the plunger cylinder 68^x, and this pressure acts to keep the valve in 105 the left-hand position as shown in Fig. 8.

The air under pressure which has passed from the cylinder through the port 33 finds egress however through the hole 52, owing to the fact that there is clearance around the stem portion 81 of the valve which carries the left hand head 69. This pressure acts against the grooved piston head 76 and overbalances the pressure against the end of the right hand plunger 69^x, with the result that the valve is moved over to the right, whereupon the passage 24 becomes open to pressure through the face port 28 and the chambers 66 and 63, and the port 22 is opened to exhaust. The drill plunger is then re-tired backward by the pressure against its front end, but as soon as its forward end passes over the aperture 35, pressure passes thence to the valve operating port and acts on the right hand end of the grooved piston 115 77 and throws the valve back to the original left hand position. It will be seen, therefore, that with this setting of the manual control tube valve 90, the drill plunger is reciprocated through a short stroke in the 120 125 130

back portion of the cylinder 20. Similarly for any other setting of the tube valve 90 the length of stroke permitted to the drill plunger and the position in which said plunger may work in the cylinder is determined.

In the four working positions of the tube valve 90 the by-passes are opened in the following groups viz.: No. 1, 33 and 35; No. 10 2, 34 and 35; No. 3, 34; No. 4, 36 and 37. In whichever direction the drill plunger is moving, its motion becomes reversed when it passes any one of the by-passes 33, 34, 35, 36, or 37 which is for the time being open 15 through the tube valve 90.

The cock 31 forms a short circuit from the hole 30 in the cylinder wall to the pressure and eduction passage 24. By opening this 20 cock, the pressure in the cylinder is short-circuited to the exhaust as soon as the plunger passes and so opens the aperture 30.

In operating the machine, this valve is opened when the drill is working against solid material, in which circumstances it is 25 necessary to strike unyielding blows. When however soft or irregular material is being operated on, through which the drill might at times break through rapidly, the cock 31 is closed. The piston cannot then overrun 30 its stroke, and strike the forward end of the cylinder.

In operating air or steam cradle drills of the percussive type it is known that the plunger moves in the cylinder very rapidly 35 and that when its forward movement is not arrested by the contact of the drill against solid rock the plunger frequently strikes the front end of the cylinder, and liability to mechanical injury to the machine is thus 40 always present, notwithstanding that some air cushioning space is provided and notwithstanding also that buffer rings of rubber or like compressible substance are fitted to diminish the force of such accidental 45 blows.

In my invention reversal of the main valve is effected in sufficient time to admit air into the front end of the cylinder before the plunger has completed its stroke, the 50 driving pressure behind the plunger escaping to exhaust at the same time as the pressure is admitted to the front end of the cylinder. The pressure in the front of the plunger in this case buffers it, but the machine does not strike its blows as solidly as is 55 possible when the plunger is permitted to make its stroke without air buffering. The provision of the control valve 31 in this invention gives the operator command of the 60 machine so that he may adjust it by merely turning the valve 31 by a hand lever to operate with best efficiency under either working condition, that is to say against a solid unyielding face or in soft or irregular material. 65 It is to be noted that the relief of air pressure

from the front of the plunger by short circuiting through the valve 31 does not effect reversal of the main valve by said by-passed air going through the holes 33, 34, 35, 36, or 37 and acting on the main valve, because the 70 by-passed air is wire-drawn and finds a free exit through the main port 42. By adjusting the valve 31, any necessary degree of buffering may be provided for, and the operator therefore has adequate control so 75 that he may suit the action of the drill to the particular conditions in which it is working.

Depending on the position to which the tube valve 90 is turned in its seating, any 80 one or two of the by-pass holes 33 to 37 is opened to the groove passage 50, and so pressure air is delivered from the cylinder to reverse the main valve when the plunger head has overrun the particular by-pass hole 85 or holes which are so set opened by the adjustment of the tube valve 90. Consequently the range of stroke of the plunger is fully controllable, as also is the position in the cylinder in which a limited length of stroke 90 is permitted to said plunger.

The two controls necessary to be manipulated by the operator to govern the stroke of the plunger and its reciprocating locus in the cylinder are the rotation of the tube 95 valve 90 to an appropriate position to connect up the required by-passes to the valve reversing device, and the adjustment of the valve 31 in full open, full closed, or partially open position. Heretofore one pair 100 of by-passes has been provided to convey pressure air from either end of the cylinder to the valve operating device, but with only one pair of by-passes the stroke of the plunger is always identical, and it is not 105 practicable for the operator to vary the length of the stroke or to jig the plunger for the purpose of loosening the drill when the same is fouled or jammed.

What I claim as my invention and desire 110 to secure by Letters Patent is:—

1. In a device of the character described, the combination of a valve casing, a cylinder connected to said casing, said cylinder having a series of by-pass openings through 115 its wall and also having a passage therein leading from the forward portion of said cylinder to said casing, there being a by-pass intermediate the ends of said passage between the latter and the interior of the 120 cylinder, a valve mounted for manipulation in said by-pass, and a rotary valve having a series of angularly disposed ports a plurality of which is adapted to simultaneously align with a plurality of the by-pass openings in the cylinder wall.

2. In a device of the character described, the combination of a cylinder having a series of by-pass openings through its wall, said openings being spaced unequal distances 125

apart, a valve having a series of angularly disposed ports a plurality of which is adapted to align simultaneously with a plurality of said by-pass openings respectively, 5 and a valve casing connected to said cylinder and adapted to communicate therewith through said valve.

3. In a device of the character described, the combination of a cylinder having a 10 series of by-pass openings through its wall, said openings being spaced unequal distances apart, a tube valve having a series of angularly disposed ports a plurality of

which is adapted to simultaneously align with a plurality of said by-pass openings respectively and a valve casing connected to said cylinder, there being a passage from the end of said tube valve through the cylinder wall to establish communication between the cylinder and valve casing. 15

In testimony whereof I have affixed my signature in presence of two witnesses.

JAMES FLETCHER.
